UNITED STATES PATENT OFFICE

WILLIAM M. SCHOLL, OF CHICAGO, ILLINOIS

ARCH SUPPORT

Application filed August 26, 1927. Serial No. 215,571.

The invention relates to improvements in arch supports and more particularly to a novel device of this character which will support the inner longitudinal arch and also the 5 transverse arch of the metatarsus.

The bones of the human foot are arranged to form four distinct arches resulting in tri-podal bearing points located under the os calcis, the first and the fifth metatarsal 10 bones, respectively, or the heel and the great and the small toe joints.

In many cases of diseased, deformed feet the inner longitudinal arch becomes weakened or broken down. The weakening of this 15 arch induces an unnatural condition and weakening or depression of the arch of the metatarsus. An attempt to restore either one of these arches alone, to its natural position, is not always attended with success.

20 In conditions above pointed out, I have found it to be very advantageous to render aid to both of the aforesaid arches, by combining in one structure means to restore the bones of the foot, of both the arches, until they 25 become sufficiently strengthened, as a result of being thus relieved of undue pressure, to perform their respective natural functions.

One of the objects of the invention is to 30 provide, in one structure, a support for a longitudinal arch of the foot and the arch of the metatarsus.

Another object of the invention is to provide an arch support which has an outward 35 swing to cause it to lie more intimately under the outer portion of the foot and to more satisfactorily support the under plantar surface of the foot below the longitudinal arch.

Another object is to provide an arch support 40 for the metatarsus, comprising a longitudinally curved metal plate and a leather cover plate, and so fashioned that the second and third metatarsal bones rest above the end of the transversely curved part of the metal plate, upon a yielding cushion provided by the cover plate, and by which the heads of the first and fifth metatarsal bones remain substantially unsupported by the aforesaid metal plate. The fourth metatarsal bone is also 45 supported by the plate but not to the extent

that the second and third metatarsal heads are supported.

Another object is to provide a metal under plate for an arch support, which is curved upwardly on one side to support the inner longitudinal arch and which extends to the metatarsus and is transversely curved to underlie only the second and the third metatarsal heads. 55

Other objects, advantages and benefits will 60 readily appear to persons skilled in the art from a consideration of the specification and accompanying drawings forming a part hereof, wherein:

Figure 1 is a central longitudinal section 65 of the device.

Figure 2 is a plan thereof showing the outlines of a human foot.

Figure 3 is a central vertical section 70 through a shoe showing the arch support in place.

Figure 4 is a transverse section taken on line IV—IV of Figure 2.

Figure 5 is a transverse section taken on line V—V of Figure 2. 75

In all the views the same reference characters are used to indicate similar parts.

The metal plate 10, of the arch support, is longitudinally curved on its inner edge from 80 its rear end to a point near its front end to support the inner longitudinal arch of a foot.

The front curved end of the metal plate is also transversely curved, as shown in Figure 4, and extends under the second, third and fourth metatarsals. The mid portion of the plate is up curved at its inside edge, as shown by dotted line 12—12 of Figure 2 and as at 12 in Figure 5 to lie neatly under the instep or the plantar surface of the inner longitudinal arch. 85

The plan outline defined by line 11 shows that the rear end of the plate 10 does not extend under the heel but only to the tuberosity of the os calcis and that the outer rear end is cut away, as at 13 to permit the part of the heel overlying this portion of the plate to be unaffected thereby. 95

The overlying leather cover plate 14, is 100 longer than the metal plate and is preferably

skived at its marginal edges. The cover plate is split at its front end, as shown in Figure 1, to provide an upper flap 14^a and a lower flap 14^b. Between the flaps 14^a and 14^b a 5 yielding tapered cushion 15 is inserted and the flaps are then cemented together and to the cushion.

The cushion insert may be of sponge rubber, felt, or the like, as more specifically disclosed in my copending application Serial 10 No. 215,572 filed contemporaneously herewith.

The cushion 16 which underlies the intermediate metatarsals is shown in elevation in Figure 5. The plates 10 and 14 may be secured together by rivets 17.

15 The approximate location of the metatarsal heads are shown at 1^a, 2^a, 3^a, 4^a and 5^a.

I am aware that many changes may be made, and numerous details of construction 20 may be varied through a wide range without departing from the principles of this invention, and I therefore do not purpose limiting the patent granted hereon, otherwise than necessitated by the claims.

25 Having described my invention what I claim is:

1. In an arch support, a metallic plate longitudinally curved to support the inner longitudinal arch of a foot, said plate being transversely curved adjacent the anterior portion thereof to underlie the second and third and fourth metatarsal heads in such a manner as to give more support to the second and third heads of the metatarsus than to the fourth, said plate being cut away adjacent the rear portion thereof to permit the rounded portion of the heel to rest off the plate.

2. An arch support comprising a metallic plate longitudinally curved to support the inner longitudinal arch of a foot, said plate being transversely curved adjacent the anterior portion thereof to underlie the second and third and fourth metatarsal heads in such a manner as to give more support to the second and third heads of the metatarsus than to the fourth, said plate being cut away adjacent the rear portion thereof to permit the rounded portion of the heel to rest off the plate, a flexible covering on and extending beyond said plate, and a cushion incorporated with said covering so as to underlie the second and third and fourth metatarsal heads.

3. In a device of the character described, a metallic plate longitudinally curved to support the longitudinal arch of a foot, said plate being transversely curved to support the metatarsal arch by underlying only the second and third and fourth metatarsal heads, a flexible covering over said plate and extending therebeyond, said plate being cut away at the rear portion thereof to permit the rounded portion of the heel to rest on said covering but off the plate, and a cushion incorporated with said covering and resting on 60 the transversely curved portion of said plate

for supporting only the second and third and fourth metatarsal heads.

4. In a device of the character described, a relatively stiff plate longitudinally curved to support the longitudinal arch of a foot, 70 said plate being transversely curved to support the metatarsal arch, a flexible covering over said plate, the forward portion of said covering being split to form a pair of superposed flaps, and a cushion element held between said flaps for supporting the metatarsal arch.

In testimony whereof I have hereunto subscribed by name at Chicago, Cook County, Illinois.

WILLIAM M. SCHOLL.
